UNITED STATES PATENT OFFICE

FRANÇOIS LEPAGE AND ANTOINE MARTINEAU, OF MONTREAL, QUEBEC, CANADA

PACKAGE OPENER

Application filed December 24, 1931. Serial No. 583,075.

The present invention relates to improvements in package opening devices and has for its important object to provide means for quickly and conveniently opening a package 5 to facilitate withdrawal of the contents.

A further object of the invention is the provision of means for conveniently opening packages of the type widely employed for cigarettes and cigars without necessitating 10 the removal of gloves which may be worn by the purchaser thereof.

Another object of the invention is the provision of package opening means disposed so that by continuous pulling movement of a 15 cord the seal of the package may be torn, the interior slidable container section extended and the cover portion adjusted to an open arrangement, enabling convenient withdrawal of the contents of the package.

20 Still another object of the invention is the provision of package opening means designed so that, simultaneously with the opening of the package the top portion of the wrapper may also be adjusted to a position uncovering 25 the upper portion of the contents.

Other objects and advantages of the invention will become apparent as the description progresses.

In the accompanying drawings forming a 30 part of this specification and in which like reference characters are employed to designate corresponding parts throughout the same:

Figure 1 is a perspective view of the preferred 35 form of the invention in closed and sealed arrangement.

Figure 2 is a fragmentary perspective view illustrating the seal tearing operation.

Figure 3 is a similar view showing the 40 following step of sliding the interior package section to an extended, dispensing position,

Figure 4 is a similar view showing the next successive steps wherein the inner section cover is swung to an open arrangement and 45 the wrapper is dislodged to expose a portion of the package contents,

Figure 5 is a longitudinal section through the package, as shown in Figure 1,

Figure 6 is a similar view illustrating the 50 sections in extended open arrangement,

Figure 7 is a front elevational view showing the upper portion of the package sections broken away,

Figure 8 is a transverse section taken 55 through the upper portion of the package,

Figure 9 is a longitudinal section showing the container section in a partly extended position,

Figure 10 is a front elevational view of 60 the package in full open position with a cigarette partly withdrawn therefrom, and

Figure 11 is a perspective view of a modified form of the invention with the package in open arrangement.

Referring to Figures 1 to 10, inclusive, 65 wherein is illustrated the preferred embodiment of the invention, the numeral 20 designates the exterior section of a package of a type commonly employed in the distribution of cigarettes and similar merchandise. 70 The section 20 is of relatively flat elongated form having a rectangular cross section and open at the ends.

Fitted within the outer section 20 and disposed to be slidable relative thereto is an interior container section, generally indicated 75 at 21. This container section is of the usual folded structure embodying a full length back wall 22, a transverse bottom piece 23 and a front wall 24 extending from the bottom to a point terminating short of the top of the section. A pair of relatively narrow complementary side walls 25 are usually connected with the side edges of the back wall 80 but often disconnected from the front wall. 85

The upper covering portion of the container embodies a top piece 27 having formed integral with the forward edge a flap 28 disposed to normally extend over the upper 90 front portion of the container. The rear edge of the top piece 27 is integrally connected with a back piece 29 embodying the upper portion of the container back and disposed to swing rearwardly about a predetermined folding line formed in the back of the 95 section.

A main opening cord is connected with the package so that the rear extremity is extended through an opening in the top piece 27 and knotted interiorly thereof. This cord, 100

designated at 31, is then trained to extend rearwardly over the top surface of the top piece and downwardly over the outer face of the back, from whence it is continued under the bottom piece 23 and, when the inner section is in retracted or closed position, upwardly against the front wall 24. A portion of the cord 31 is, however, threaded through an aperture 32 in the exterior section 20 upwardly against the outer side of the front wall thereof and threaded so as to extend inwardly of the exterior section through an elevated aperture 33. The forward portion of the string is arranged in a diagonally extending position from the aperture 33 between the interior and exterior sections and extends out of the package adjacent one corner to provide a finger engaging extension 34.

20 The merchandise in the package, in the present instance cigarettes indicated at 36, is frequently enveloped in a wrapper 37, usually moist-proof paper or the like. In order to automatically open the wrapper upon 25 opening operation of the package, an auxiliary string 39 is connected to the exterior package section 20 adjacent one upper corner and is attached to the opposite corner portion of the wrapper, as shown to advantage in Figures 4 and 10.

It is also customary, upon completion of the packaging operation, to affix a seal to the top of the package, as for instance an excise stamp, as designated at 41. This 35 stamp is to be attached, by means of adhesive, to the top face of the piece 27 and folded over to be secured to the upper exterior portion of the exterior package section 20, as illustrated in Figure 1.

40 To open the package for initial extraction of one or more cigarettes, it is merely necessary to grasp the main cord extension 34 and to draw the same upwardly to a normal straight line position, causing the cord 45 to travel in a transverse vertical plane so as to tear through the seal or excise stamp 41. Upon continued upward pulling movement 45 of the cord the inner section will be successively projected through one end of the outer section to a predetermined dispensing position, that is, until arrested by the loop of the cord extending through the outer section. During the extended movement of the inner package section, it is preferable to swing 55 the upper end of the cord away from the top of the container section so as to permit the upper covering portion including the pieces 27, 28 and 29 to be swung rearwardly and to uncover the top of the container, as shown to advantage in Figures 4 and 6.

50 Simultaneous with the extended adjustment of the inner container section, a portion of the wrapper is unfolded from the upper portion of the section through the medium of the connection of the cord 39.

Consequently, when the main cord has been fully extended the inner container section of the package will be projected upwardly, the covering portion thereof removed to uncover the upper portion of the contents and a portion of the wrapper unfolded so that a cigarette may be conveniently extracted. The inner section may be restored to its normal closing position by placing the covering portion thereof in a covering position and slidably forcing the inner container section within the exterior covering section. Thereafter, the opening operation may be repeatedly executed through the medium of the opening cord without the necessity of severing the sealing member.

70 In the modification of the invention, shown at Figure 11, the package, which is of relatively large size for accommodation of cigars, embodies exterior and interior sections 43 and 44 similar in construction to those of the preferred form. The opening is effected through the medium of a cord 45 associated with the sections in a manner corresponding to that of the cigarette package but, in this 75 case, the auxiliary cord is eliminated inasmuch as the cigars may be disposed in individual wrappers.

80 As will be noted, the present construction affords a package structure having means associated therewith which will greatly facilitate the opening thereof and which will enable a purchaser to conveniently extract a unit article even though wearing gloves, which would render the opening of the present type of package extremely difficult and 85 awkward.

90 It is to be understood that the forms of our invention herein shown and described are to be taken as preferred examples of the same, and that various changes as to the shape, size, and arrangement of parts may be resorted to without departing from the spirit of the invention or the scope of the subjoined claims.

95 Having thus described our invention, we claim:

1. In a package, the combination with an exterior package section and an interior section slidable within the exterior section, of an opening cord having one end attached to the interior section and slidably secured to the outside section, said cord being arranged on each section so that by predetermined pulling the fastening seal of the package will 105 be severed, the interior container section slidably extended to a limited dispensing position and the top portion of the inner section 110 swung from a covering to an open position.

115 2. In a package, the combination with an exterior package section and an interior section slidably fitted within the exterior section, of an opening cord having one end fastened to the top portion of the inner section 120 and extending about the section, a portion of 125

the cord being looped through the exterior section and including a free end adapted to extend from the package whereby pulling of the cord will cause extension of the inner section to a dispensing position and simultaneous opening movement of the top.

3. In a package, the combination with an exterior package section and an interior section slidably fitted within the exterior section, of an opening cord having one end fastened to the top portion of the inner section and extending about the section, a portion of the cord being looped through the exterior section and including a free end adapted to extend from the package whereby pulling of the cord will cause extension of the inner section to a dispensing position and simultaneous opening movement of the top, an auxiliary cord having one end fastened to the exterior section and the opposed end to a portion of the package wrapper whereby the wrapper will be partially unfolded when the interior section of the package is extended.

20 In witness whereof we have hereunto set
25 our hands.

FRANÇOIS LEPAGE.
ANTOINE MARTINEAU.
